[57] **CLAIM**

The ornamental design for a combined dispenser and container for cosmetics and hair care products, as shown and described.

DESCRIPTION

FIG. 1 is an overhead perspective view of a combined dispenser and container for cosmetics and hair care products showing my new design;

FIG. 2 is an overhead perspective view from the opposite side;

FIG. 3 is a front elevational view;

FIG. 4 is a rear elevational view;

FIG. 5 is a top plan view;

FIG. 6 is a bottom plan view;

FIG. 7 is a right side perspective view; and,

FIG. 8 is a left side perspective view.

The broken line showing of bottles and a receiving cup is for illustrative purposes only and forms no part of the claimed design.

FIG. 1

FIG. 2

FIG. 3

FIG. 4
